JUSTIFYING TYPEWRITER

Elihu Root, III, Springfield, Vt., assignor to Research Corporation, New York, N. Y., a corporation of New York

Continuation of application Serial No. 479,933, March 20, 1943. This application January 28, 1947, Serial No. 724,778

44 Claims. (Cl. 197—19)

1

This invention relates to justifying typewriters and particularly to certain physical constructions and electric circuits in the machine disclosed and claimed broadly in Patent No. 2,379,862, issued July 10, 1945, to Vannevar Bush.

The present application is a continuation of my application Ser. No. 479,933, filed March 20, 1943, and since abandoned, for "Justifying typewriter."

An object of this invention is to provide a novel variable escapement mechanism, useful for certain purposes which will appear, and also to provide a novel electro-mechanical memory unit for recording and subsequently transcribing signals characteristic of the manual operation of the keys of a typewriter. It is also my object to provide further mechanical and electrical devices as will be pointed out in the appended claims.

In the drawings:

Fig. 1 is a block diagram of the principal elements of a justifying typewriter embodying the invention;

Fig. 1a is a diagrammatic end elevation, with parts broken away, of a keyboard unit for the justifying typewriter, the unit being a conventional non-justifying typewriter to which a bank of key-controlled switches has been added;

Figs. 2a, 2b and 2c are fragmentary circuit diagrams which, when laterally aligned, constitute the circuit diagram of an embodiment of the invention;

Fig. 3 is a fragmentary circuit diagram of the word space selector switch and associated stop solenoids of the carriage escapement mechanism;

Fig. 4 is a circuit diagram of the decoding system;

Fig. 5 is an elevation of the line length and word space index;

Figs. 6 and 7 are circuit diagrams of the line length and word space indexes, respectively;

Fig. 8 is a plan view of the first variable escapement that is a part of the line length counter mechanism;

Fig. 9 is a side elevation of the same;

Fig. 10 is an enlarged scale fragmentary plan view of the clutch mechanism of the escapement mechanism;

Fig. 11 is a perspective view of the switch systems of the escapement mechanism;

Fig. 12 is a perspective view, on a greatly enlarged scale, of the clutch-controlling elements of the escapement mechanism;

Figs. 12a and 12b are fragmentary side elevations illustrating the clutch-controlling elements in different positions of adjustment;

2

Fig. 13 is an end elevation of the variable escapement of the justifying typewriter;

Fig. 14 is an enlarged scale, fragmentary plan view of the same, with parts shown in section;

Fig. 15 is a fragmentary rear elevation of the carriage escapement rack and the pawl and ratchet connection between the same and the variable escapement mechanism;

Fig. 15a is an end elevation, as seen from below, of the pawl and ratchet connection;

Fig. 16 is a plan view of one of the memory units;

Fig. 17 is a side elevation of the same;

Figs. 18 and 19 are enlarged scale, fragmentary end and side elevations, respectively, of the band-advancing mechanism of the memory units, the Fig. 19 section being on the plane of line 19—19 of Fig. 16;

Fig. 19a is a fragmentary perspective view, with parts broken away, of the clutch and associated elements of a memory unit;

Fig. 20 is a fragmentary sectional view, as seen on the plane indicated by section line 20—20 of Fig. 22, of a band of a memory unit and the solenoid-operated mechanism for recording a key actuation on the band;

Fig. 21 is a similar fragmentary plan view in which the mechanism is illustrated in the positions assumed upon the energization of a code-recording solenoid;

Fig. 22 is a fragmentary side elevation of the end of a recording band, the associated code-recording mechanism, and decoding switches;

Fig. 23 is a fragmentary sectional view of the band and decoding switches as seen on the section indicated by line 23—23 of Fig. 22; and

Figs. 24 and 25 are enlarged scale, perspective views as seen from above and below, respectively, of a portion of a memory unit band and code-recording elements.

For a clearer understanding of the cooperative functions of the various electrical and mechanical devices constituting my present invention, I shall describe herein a complete justifying typewriter in which my invention has been embodied. Those elements which constitute my invention will be pointed out in the claims appended here-to.

The several functional units of the justifying typewriter and their relationships are shown in the block diagram of Fig. 1. The keyboard KS may be a bank of key-operated switches carried by any suitable base but it is preferable to form this unit of the justifying typewriter by mounting the switches 1 below the keys of a conventional

non-justifying typewriter T, see Fig. 1a. The key-actuated switches control current flow to individual relays of a bank of coding relays C which reduces the large number of individual key signals to some combination of a small number of code elements. The usual typewriter has about 50 keys or operation-controlling members, and a 6-element code provides 64 combinations that may be used to identify the different key or control member operations. The coding of the signals is not essential but it simplifies the design of the memory units M', M'' which record the sequence of the key operations. The coding relays C have the additional functions of energizing the word space counter S to record the number of word spaces, i. e. the number of operations of the word space bar, and of actuating the first variable escapement V1 in accordance with the width of the several characters and the minimum word space. The accumulated length of the unjustified line is recorded in the line length counter U. When the complete line is recorded in memory unit M', the operator returns the carriage of the non-justifying typewriter T to starting position and in so doing energizes the transfer switches Tr to connect memory unit M' to the decoding relays D and to connect memory unit M'' to the coding relays C. The word space control unit SS divides the difference between the recorded and the justified line length by the number of word spaces to determine the necessary increase for each word space, and records the result as a control to be imposed upon the variable escapement V2 of the justifying typewriter unit JT. At the completion of this computation, the memory unit M' transcribes the recorded line by energizing the decoding relays to select in sequence those operating circuits of the typewriter unit that correspond to the recorded key operations. The current pulses corresponding to characters go directly to the typewriter unit to energize the solenoids O that operate the type bars and to the carriage escapement V2 to advance the same in accordance with the widths assigned to the several characters. The current pulses corresponding to word spaces are shunted through the word space control unit SS in which the computed word space value for line justification was recorded, and this computed value controls the carriage advance by the escapement V2 when a word space is entered in the typed line.

Coding relays

The circuit diagram of the apparatus, Figs. 2a-2c, shows only a few of the character key switches 1a, 1b, etc., as the key switches are all of the illustrated single pole type for completing a circuit from the current source (indicated by the symbol +) through the associated character relay 2a, 2b, etc. in the bank of coding relays C, and then through a common lead 3 to the record-advancing device in the memory unit. Each coding relay, when energized, closes a normally open switch c in the coding system and a normally open switch e in the escapement-control system. Each coding switch c has from one to six movable blades for energizing one or more of the six lines of the coding cable 4 in accordance with the particular code identifications assigned to the letters, numerals and other characters. If the letter "A" has, for example, the code identification "25," the switch c of relay 2a will have two movable blades for connecting the "2" and "5" lines of the code cable to the + terminal of the power source. 75

Shift key control

The blades of the switches e of the coding relays 2 are connected to the + terminal and, in general, the front contacts are connected by leads 5 to the blades of the outer group of double throw switch sections of the relay 6 that is controlled by the "shift key" switch 7 to regulate the space allotted to characters that have "lower case" and "upper case" type faces of different widths. The character spaces are measured in "escapement units" that are substantially smaller than the width of even the narrow letters and symbols, and may vary from three to eighteen units in the particular embodiment that will be described later. The function of the relay 6 is to determine the advance of the escapement mechanism V1 in accordance with the energized coding relay 2 and the position of the shift key switch 7. If, for example, the letter "a" is allotted a space of 9 escapement units and the letter "A" a space of 13 escapement units, the lead 5a from switch e of relay 2a is connected to a blade of relay 6 that has the back and front contacts connected to the "9" and "13" lines, respectively, of the escapement control cable 8. The leads 5 extend from switches e directly to lines of the escapement control cable in the case of coding relays 2 energized by keys whose upper case and lower case characters are of the same width.

The shift key is preferably of the conventional type that may be locked down, at the option of the operator, for typing a group or line of upper case characters. The relay system controlled by key 7 therefore includes a slow-acting relay 6S in parallel with the relay 6, and interconnected switches of these relays for transmitting a signal to the recording memory unit at the closing, and at the opening, of the shift key switch 7. The front and back contacts of the inner double throw switch sections of relays 6S and 6 are reversely connected to each other, the switch blades being connected respectively to the + terminal and, through lead 3s, to the common lead 3 to the record-advancing device of the recording memory unit.

The + terminal is connected to the blade of the outer switch section of relay 6S, and the cooperating contacts are connected to blades of the two single throw switch sections of relay 6 to determine the code signal to be recorded in the memory unit. More specifically, the back contact of the relay 6S is connected to a blade of relay 6 that has a front contact connected by lead 6U to a line of coding cable 4 that corresponds to an upper case or "shift" signal, and the front contact of the relay 6S is connected to a blade of relay 6 that has a back contact connected by lead 6L to another line of the coding relay 4 that corresponds to a lower case or "shift release" signal.

An actuation of the shift key to close the switch 7 energizes the relays 6 and 6S, but the armature of relay 6 responds more quickly than that of the slow acting relay 6S. The outer blade of relay 6 thus connects the lead 6U to transmit an "upper case" signal to the recording memory unit before the blades of relay 6S move to engage their front contacts. The inner blade of relay 6 functions at the same time to send a current pulse through leads 3s, 3 to the record-advancing device of the memory unit. These impulse-transmitting circuits are then opened when the armature of the slow-acting relay 6S is attracted to its core. The shift key may be released after a single character key or

a number of character keys are operated. The armature of relay 6 is released quickly upon an opening of switch 7, and the intermediate blade of relay 6 thus connects the lead 6L, corresponding to a "lower case" signal, to the + terminal through the front contact of the outer blade of relay 6S before the armature of that relay is released. The inner blade of relay 6 engages its back contact before the inner blade of relay 6S leaves its front contact, and a current pulse is thereby transmitted to the record-advancing device of the memory unit. The armature of the slow-acting relay 6S then drops out to open these circuits, as shown in Fig. 2a.

First variable escapement V1

The variable escapement includes a shaft 9 that is turned clockwise by a spring, not shown in Fig. 2b, when a current pulse is transmitted through the selected line of the cable 8 to one of the stop-solenoids 10 and to the escapement-trip solenoid 11 which controls the shaft advance device that is shown schematically as a pawl and ratchet 12. The circuits of all of the stop-solenoids 10 are completed to ground through the solenoid 11, and a second energizing circuit for solenoid 11 includes the zero resetting solenoid 11e. The stop-solenoids 10 are radially arranged about the shaft 9 and selectively project stop members, not shown in Fig. 2b, into the path of a radial lug on the shaft 9. This illustration of the escapement control is schematic and intended to facilitate an understanding of the correlation of the operations that are effected or controlled by the solenoids 10, 11 and 11e. Appropriate physical structure will be described later and, for present purposes, it is sufficient to state that each escapement advance is effected by the transmission of a current pulse through one of the stop-solenoids 10 and the escapement-trip solenoid 11 in series. The energized stop-solenoid determines the number of units of angular advance of the shaft 9 that is effected when the pawl and ratchet 12 is tripped by the solenoid 11. When the solenoids 11 and 11e are simultaneously energized, the pawl and ratchet is tripped to reset the shaft 9 to a definite zero position before the starting of a line length measurement.

Line length counter

The length of the composed line is recorded in terms of rotations of the shaft 9, each rotation corresponding to a large number, for example twenty, escapement units. The shaft rotations or groups of twenty units are recorded by stepping relay U in bank U2 of a stepping switch by a circuit including a switch 13 controlled by a cam 14 on the shaft 9. Switch 13 energizes the relay 15 once for each rotation of the shaft to transmit a current pulse to the brush of the switch bank U2 through the contacts of relay 15 before they open. The end contact of the bank U2 is connected through lead 16 to the relay X of the computing system, and all other contacts are connected through the lead 17 to the stepping relay U. For simplicity of illustration, a single bank U2 of 25 contacts and a diametrical brush are shown but it is usually preferable to employ two switch banks with oppositely directed radial brushes, thereby adapting the line length counter to register up to 50 rotations of the shaft 9 of the variable escapement. This permits a maximum of about 100 characters in the average line of the maximum length, but there is no critical upper limit to the line length

and the apparatus may be designed for longer line lengths by employing a stepping switch that will record a greater number of rotations of the escapement shaft 9.

The length of the justified typed line may be adjusted manually by the line-length switch L which has contacts connected to the contacts of the switch bank U1 of the stepping switch, and a contact arm that is connected to the + terminal of the power source. The brush of the switch bank U1 is grounded through the "line stop" relay US which has normally closed contacts in series with the stepping relay U and its normally closed contacts, and with the resetting lead 18 that extends to the + terminal through normally open contacts of the relay H that will be described later.

The effective length of the justified line is determined by the number of steps or contacts between the "hot" contact of bank U1 and the end contact, each step corresponding to one rotation of the shaft 9 and thereby to twenty escapement units. The longest line length is obtained when the contact arm of the line length switch L is moved clockwise to engage the upper switch point, and the line length is decreased in steps of twenty escapement units as the contact arm is turned to shift the "hot" contact of bank U1 towards the end contact. The blades of switch banks U1, U2 are reset to bring the blade of bank U1 on the hot contact at the end of one justification-computing operation, i. e. the recording of the length of the next composed line starts with the blade of bank U1 in the position illustrated in Fig. 2b.

The shaft 9 of the escapement mechanism carries the blade of a 20 point switch E that registers the escapement units or partial rotations of the switch 9 beyond the full rotations that are registered in the switch bank U2. The several contacts of the switch E are connected, in reverse sense, to the 20 contacts of the switch bank R1 of a "negative remainder" counter or stepping switch of the justification computing system.

Memory unit

The memory units M', M'' are of identical design, and appropriate physical constructions will be described later. For an understanding of the electrical circuits of the memory units, it may be assumed that each unit includes a movable band or bands upon which the keyboard switch operations are recorded in code combinations by one or more of six coding devices, and six decoding switches that are subsequently closed by the movable band or bands in accordance with the recorded codings. In Fig. 2c only one recording magnet 19 and one decoding switch 20 are illustrated. The several lines of the coding cable 4 are connected to recording magnets 19 of one or the other memory unit through the double throw switches 21 of the transfer device Tr and the cables 4', 4'' that extend from the transfer switches to the respective memory units. The several decoding switches 20 of the memory units are connected through decoding cables 22', 22'' to the fixed contacts of double throw transfer switches 23 in the transfer device Tr, and the movable blades of these switches 23 are connected through the decoding cable 24 to the assembly of decoding relays, indicated generally by the block diagram D, that selectively establish circuits for energizing the several operations-controlling and character-printing solenoids of the electrically operated justifying typewriter JT.

Memory units M', M'', include solenoids 26',

28" for effecting a step-by-step advance of the recording band or bands, the leads 27', 27" for energizing the solenoids extending to the movable blades of the double pole, double throw switch section 28 of the transfer device Tr. The switch 28 connects the leads 27', 27", in alternation depending upon the recording or transcribing function of the memory units, to the lead 3 from the coding relay bank C or to the outer movable blades of double throw switch units or memory relays 29', 29" that are alternatively energized through the switch section 30 of the transfer device Tr. With the parts in the positions illustrated in Fig. 2c, the transfer device Tr connects the coding cable 4 to memory unit M' for the recording of key operations, and connects memory unit M' to the justifying typewriter JT through the decoding cable 24 for the transcribing of the character and operations signals that were previously recorded in the memory unit M''. Each recorded signal is "erased" or removed from the moving bands after the signal passes the decoding switches 20.

The circuits of the memory relays 29', 29" are completed to ground through the leads 31', 31", normally closed clutch switches 32', 32", and clutch-operating solenoids 33', 33" of the respective memory units M', M''. Each memory relay 29' or 29", when initially energized by the switch section 30 of the transfer device Tr, completes a holding circuit through the front contact of the inner double-throw switch section of the energized relay. The back contacts of these switch sections of relays 29', 29" connect the + terminal to the decoding switches 20 of memory units M', M'' through leads 34', 34" respectively. The outer sets of double throw switches of the memory relays complete circuits for supplying current pulses to the band-advancing solenoids 26', 26" at the completion of a recording operation and during a transcribing operation. The lead 27', 27" that is not connected by the transfer switch section 28 to lead 3 is connected, through jumper 35' or 35", respectively, to the movable blade of the outer switch section of the associated memory relays 29', 29". The back contacts of these switch sections are connected to each other and, through lead 36, to the blade of the intermediate single throw switch section of relay R' of the justification computing system, the front contact being joined to the outer switch section of the impulse relay I and, through lead 37, to the front contacts of the outer switch sections of both memory relays 29', 29".

When, as illustrated, the transfer switch 28 is adjusted to energize the relay 29' of the memory unit M' for a recording of key actuations in that unit, the band-advancing solenoid 26' is connected through lead 27' and switch 28 to the lead 3 from the coding relays C, and the band-advancing solenoid 26" of the memory unit M'' is connected to current-supply contacts of the impulse relay I through lead 27", switch 28, lead 35', the outer front contact of relay 29" and the lead 36.

The several switches of the transfer device Tr will be shifted to their alternative positions at the completion of the recording of a composed line in memory unit M', and the switch section 30 will then transfer the + terminal connection to the memory relay 29" of unit M'' to condition the same for a recording operation, but the relay 29' of unit M' will remain locked-in by its holding switch section. The band-advancing solenoid

5 28" of unit M'' will then be connected to the lead 3 from the coding relays C by switch 28, and the corresponding band-advance solenoid 26' or unit M' will be connected to switch contacts of impulse relay I through lead 27', switch 28, lead 35', and the front contact of the outer switch section of relay 29".

10 The stated actuation of the transfer device Tr connected the coding cable 4 to the recording magnets 18 of the memory unit M'' at the switch 21, and connected the decoding switches 20 of memory unit M' to the decoding cable 24 at switches 23. The switches 20 of unit M' are not connected to the + terminal, however, so long as the relay 29' remains energized through its holding switch. Relay 29' is de-energized by the opening of the switch 32' which is a limit switch actuated by a measuring device that is coupled to the movable recording band by the clutch solenoid 33'. The number of coded signals in a recorded line will vary with the average width of the series of signals, and the recording bands must have a length at least equal to the maximum number of signals that may constitute a line plus the maximum number of "steps" that the bands are advanced during the computation of the line justification. The function of the clutch solenoid 33' and the measuring device is to open the switch 32' only when the first signal placed on the band, after an energization of the clutch solenoid 33', is under the decoding switches 20 to actuate the same to deliver current pulses to the decoding relays D upon the next energization of impulse relay I to effect a step advance of the bands. In other words, switch 32' is opened to de-energize relay 29', thereby connecting the + terminal to the decoding switches 20 only when the first signal to be transcribed is under and has actuated the decoding switches.

40 "Erasure" of errors

45 This control of the switch 32' as a function of the travel of the bands after an energization of the clutch solenoid 33' provides means for "erasing" a sequence of key operations that are recorded in the memory unit. The operator may detect an error in key actuation before the composing of a line upon the keyboard is completed, or may wish to cancel a composed line, whether or not it contains a typographical error, after inspecting the line that is typed on the non-justifying typewriter T by the actuation of the keys that close the switches 1. The clutch solenoids 33', 33" may be de-energized during a recording operation in the associated memory unit M' or M'', thereby to reset the measuring device, by grounding the leads 31', 31". Jumper 38', 38" extends from these leads to the opposed contacts of the transfer switch section 39 that has a blade connected to ground through the lead 40 and the inner normally open contacts of a relay 41 that is energized by the closing of an "Error" switch 42 at the keyboard. The outer contacts of the relay 41 connect the + terminal to a lead 43 that extends to the resetting solenoid 11e of the first variable escapement V1 and the word space counter S. A closure of the error key switch 42 thus shorts out and de-energizes the associated clutch solenoid 33' or 33" to render ineffective the previously recorded signals since, as stated above, the measuring device controlled by the clutch solenoid will not open the switch 32' or 32" until, after an energization of the clutch solenoid, the first recorded code signal is in engagement with the decoding switches to transmit decoding cur-

rent pulses upon the next energization of the relay I. All signals recorded prior to the last energization of the clutch solenoid therefore move idly past the decoding switches 20 which are not connected to the + terminal until the associated memory relay 29' or 29'' is de-energized.

The closure of the error key switch 42 also functions, as will be described later, to reset the variable escapement mechanism V1 and the word space counter.

Word space counter

The keyboard space bar actuates switch 44 to close a series circuit from the + terminal to the word space coding relay 45, the lead 45' to lead 3, and then through the transfer switch 28 to the band-advancing solenoid 26' or 26'' of the recording memory unit. Energization of relay 45 closes the associated contacts to connect the + terminal to a line of the coding cable 4 through lead 46, and to the stepping solenoid S of the word space counting switch through lead 46'. The blade of the bank S1 of the counting switch is connected to the + terminal through lead 47 and contacts of relay H when the latter is energized. The end contact of the bank S1 is open, and all other contacts are joined to each other and to lead 46' through the normally closed contacts of the stepping solenoid S. The switch bank S2 is a part of the justification computing system, the contacts of the bank being connected to the several lines of the escapement cable 8, and thereby to the stop controlling solenoids of the variable escapement V1. The blade of bank S2 is connected through lead 48 to the back contact and intermediate blade of impulse relay I, lead 49, the outer blade and back contact of relay R, lead 50, the outer back contact and blade of relay K, and then through lead 51 and normally open contacts of the carriage return relay CR to the + terminal, the contacts being closed to initiate a justification computation when the carriage return relay is energized at the completion of line recording operation.

Carriage return

The carriage return switch 52 is closed by a manually actuated key or by the operation of the carriage return lever when a conventional typewriter, as modified for key actuation of the character and operations-controlling switches, is employed as the keyboard unit of the justifying typewriter. The circuit of the switch 52 extends from the + terminal through the slow acting relay CS and the outer set of normally closed contacts of the carriage return relay CR to the lead 53 that extends to a line of the coding cable 4, for example to line "4." The closing of the carriage return switch 52 thus records a coded carriage-return or end-of-line signal in the memory unit. The primary circuit for energizing the carriage return relay CR may be traced from the relay back to the + terminal through the normally closed outer contacts of the end-of-line relay EL, jumper 54, the normally open contacts of relay CS, the "home" contact of the switch bank SS1 of the word space selector stopping switch, and the blade of the bank SS1. A holding circuit for the relay CR is closed from the jumper 54 through the outer set of normally open contacts of the relay. The lead 55 extends from the energizing circuit of relay CR, at a point beyond the contacts of relay EL, to the solenoid 56 of the pawl and ratchet mechanism 57 for alternately opening and closing the switch

58 of the solenoid 59 of the transfer switches Tr.

As stated above, the energizing current for the slow-acting relay CS also serves to record an end-of-line signal in the memory unit through the lead 53 and a line of the coding cable 4. Energization of relay CS closes contacts in the supply circuit of the carriage return relay CR, but the relay CR is energized only when the brush 10 of the space selector switch bank SS1 is at its home point, i. e. only after the completion of the transcribing of the previously composed line from the other memory unit to the justifying typewriter mechanism. This will be the normal operating condition as the transcribing of the previously composed line from one memory unit will usually be completed more rapidly than the "typing" of a new line for recording in the other memory unit.

Energization of the carriage return relay CR opens its outer relay contacts in the lead 53 and thereby de-energizes the coding element that had previously placed the end-of-line signal on the recording memory unit. The relay CR is locked in through its holding contacts and the normally closed outer contacts of the relay EL, and is de-energized at the completion of the transcription of the recorded line into the typewriter JT upon the transmission of a code current pulse to the relay EL. Lead 60 connects the relay EL to the code line "4" of the decoding system, and the energizing circuit of the relay is completed through the lead 60' and the carriage return solenoid O of the justifying typewriter JT, see Fig. 4. The relay EL has a second set of normally open contacts for completing a circuit to energize the resetting solenoid 11'e of the escapement mechanism of the justifying typewriter.

Word space selector switch

As stated above, the circuit for energizing the carriage return relay CR extends through the brush and the homing contact of the bank SS1 of the word space selector switch. All other contacts of the bank are connected to each other and, through lead 61, to the normally closed contacts of the stepping relay SS, lead 62, the normally closed inner contacts of the carriage return relay CR, and jumper 63 to the energizing lead 64 of the stepping relay SS. This energizing lead 64 extends from relay SS to the front contact of the intermediate movable contact blade of the impulse relay I of the computing mechanism, and through the branch lead 64' to the front contact of the inner movable contact blade of a relay WS that is energized by current pulses transmitted through lead 65 from the decoding bank of switches D of the justifying typewriter. The blade of the switch bank SS2 is connected in series with the relay WS by lead 66, and the contacts of the bank SS2 are individually connected through the escapement control cable 67 to the several stop-solenoids 10' of the carriage escapement mechanism V2 of the justifying typewriter unit. The position of the blade of the bank SS2 is determined, as will be described later, by the computing system which divides the line remainder by the number of recorded word spaces. Each decoded word space signal thus flows, in series, through relay WS, the lead 66, the switch bank SS2, and the escapement control cable 67 to control the advance of the typewriter carriage. The several stop-solenoids 10' are returned to ground through the carriage release 70 trip to solenoid 11' in the same manner as de-

scribed above with respect to the variable escapement VI.

Justification computing and control mechanism

The composed line length is justified by increasing the widths of the word spaces during the transcribing from a memory unit to the justifying typewriter, and the computation of the justification is completed prior to the transcribing operation. The number of escapement units to be added to the original word space width is determined by dividing the line shortage u (i. e. the difference between the composed line length as accumulated by the variable escapement VI in the line length counter U and the desired line length as set on the manually adjustable switch L) by the number s of the word spaces recorded in the bank S1 of the stepping switch S. This division is carried out by a step-by-step rotation of the shaft 9 of escapement VI, from its position at the end of a line composing operation, until the blade of switchbank U2 of the line length counter reaches its end contact point, each step advance of the shaft 9 being controlled by the word space counter S and being equal to s escapement units where s , as stated above, is the number of word spaces in the composed line. The number n of step advances is counted in the word space selector SS, and the blade of the bank SS2 is thereby adjusted to determine the widths of the word spaces in the line that is printed on the justifying typewriter JT.

The quotient

$$\frac{u}{s}$$

of the line shortage divided by the word spaces may or may not be a whole number, but the computation with stepping switches will determine the number n of step advances of shaft 9 that is required to register a total number of escapement units equal to the desired line length plus not more than s escapement units. Further justification is obtained by adding $(n-1)$ escapement units to all word spaces when the quotient of the justification computation is a whole number, and by adding $(n-1)$ units to some word spaces and n units to other word spaces when the quotient is not a whole number, i. e. when the computation terminates at a registered line length that exceeds the desired line length by less than s escapement units.

The justification computing mechanism is placed in operation upon the energization of the carriage return relay CR at the completion of the recording of a composed line in one of the memory units. As stated above, the initial position of the blade of switch bank U2 is illustrated in Fig. 2b, and the recording of the composed line length will move the blade of the bank U2 towards but to a point short of its end contact that is connected to the relay K. The energization of the carriage return relay CR opens the inner contacts of relay CR, thereby opening the lead 52 to the homing circuit of the stepping relay SS of the word space selector. The two adjacent sets of switch contacts of relay CR close to connect the + terminal to the lead 51 that extends to the outer blade of the relay K, Fig. 2b, and to the lead 54 in the holding circuit of relay CR that extends through the normally-closed outer contacts of the impulse relay I and lead 59 to the slow-acting impulse relay IS that has normally open contacts for closing the circuit of relay I.

The relays I, IS thus pulsate and the inter-

mediate blade of the relay I moves back and forth to supply current pulses in alternation to lead 48 that extends to the variable escapement VI through the bank S2 of the word space counter, 5 and to lead 64 that extends to the stepping relay SS of the word space selector. The current supply to this blade of the impulse relay I is through the inner set of normally open contacts of relay CR, lead 51, the outer contacts of the de-energized relay K, lead 50, the outer contacts of the de-energized relay R', and lead 49. The supply of current pulses to escapement VI and to the word space selector SS will therefore be interrupted by the energization of relay K.

Each current pulse to escapement VI corresponds to an increase in the measured line length by the addition of one escapement unit to each recorded word space, since the advance of the shaft 9 is controlled by the stop solenoid 18 that is selected by the adjustment of the word space counter S, and the number of steps is registered in the word space selector SS. The primary computation or stepping of the escapement VI and the word space selector SS continues until 20 the additions to the initially registered line length result in a computed line length that is in excess of the desired value by s or less than s escapement units, where s is the number of recorded word spaces. The shaft 9 is advanced upon the 25 de-energization of its trip magnet 11, and the step advance of shaft 9 that results in the closure of switch 13 to move the blade of the line length switch bank U2 to its end contact conditions the 30 system for the transmission of a current pulse to the relay K upon the next closure of the switch 13. The step advance of escapement VI and the word space selector SS then continues until the shaft 9 again sweeps through its zero position to close the switch 13. This closure of switch 13 35 sends a current pulse to relay K, and also to relays H and HS that are connected in series with relay K by lead 18'. Energization of relay K opens the current supply circuit to the intermediate blade of impulse relay I, and thereby 40 stops the primary computation of line justification in the word space selector SS; and the energization of relay H completes circuits to reset the line length counter U and the word space counter S.

45 The energization of relay H connects the lead 18 to the + terminal, and thereby completes a circuit for energizing the stepping relay U through the normally closed contacts of the stop relay US and the normally closed contacts of relay U. The relay U thus takes up a rapid step-by-step operation to advance the blades of banks U1 and U2 until the blade of bank U1 reaches the hot contact to energize the relay US to open the supply circuit to the stepping relay U. The 50 word space counter S is also reset to its zero point as the energization of relay H connects the + terminal to lead 47 that extends to the stepping relay S through the switch bank S1.

55 The number of steps n of the word space selector SS is therefore equal to one more than the quotient of the line shortage u divided by the number s of word spaces, and the position of the blade switch E at the completion of the primary justification computation indicates the 60 excess line length that would result from the addition of n escapement units to each word space. A second computation is initiated by the energization of relay K to measure this "negative remainder," i. e. to determine the number of word spaces that should receive only $(n-1)$ escape-

ment units. The secondary computation system includes a stepping relay R with two banks R₁, R₂ of contacts, the number of contacts in each bank being equal to the number plus one of escapement units recorded by one revolution of the shaft 9 of escapement V1. The blade of switch bank R₁ is connected to the + terminal, the home contact of the bank is connected by lead 71 to the inner blade of relay WS, and the remaining contacts are connected to the contacts 10 of the switch E of the escapement V1. The end contact of bank R₁ is open, the next prior contact is connected through lead 71 to the inner movable blade of the word space relay WS, and the second prior contact is connected to the second contact of the switch E. The first contact of switch E is open and, beginning with the second contact of switch E, its contacts in the direction of movement of the blade of switch E are connected to the second and other contacts 15 of switch bank R₁ as counted reversely to the direction of blade movement from the end contact of the switch bank R₁. This reversal of connections between the contacts of the switch E and the contacts of switch bank R₁ provides circuit connections by which contacts of switch E, as counted in the direction of the advance of that switch blade, are connected to the corresponding-numbered contacts of the switch bank R₁ as 20 counted contrary to the movement of that switch blade. For example, the contact of switch E in the fifth position beyond the zero contact of that switch is connected to the fifth contact short of the end contact of the switch bank R₁.

As stated above, the shaft 9 of escapement V1 is advanced upon the release of its trip magnet 11, and the blade of switch E therefore rests on a contact corresponding to not more than s, the number of recorded word spaces, at the completion of the primary computation. The blade of switch bank R₁ is then stepped around by the secondary computing system to locate the position of the blade of switch E. The stepping relay R is energized by a circuit including its normally closed contacts, lead 72 to the front contact of 35 the intermediate switch blade of relay K, and lead 73 to the back contact of the inner switch section of the relay R', the blade of that switch section being connected to the + terminal by the jumper connection 74 to lead 54 and contacts of relay CR. Lead 75 connects the blade of switch E to the back contact of the inner switch section of relay WS and to relay R'. The front contact of the inner switch section of relay R' is connected by lead 76 to the slow-acting relay RS and to the inner switch blade of that relay. The stepping relay R thus steps around rapidly until the blade of bank R₁ reaches the contact that is connected to the switch E contact then engaged by the blade of that switch. A current pulse is then delivered to relay R' through lead 75, and the energization of relay R' in turn opens the current supply circuit to the stepping relay R and transmits a current pulse through the lead 76, the back contacts of slow-acting relay RS, jumper 77 and lead 43 to energize the resetting trip solenoid 11e of the escapement V1. The current flow through lead 76 also energizes the slow-acting relay RS and, when this relay pulls in after a slight delay, its inner set of contacts open to interrupt current flow to the jumper 77. The relay R' is locked in through its outer single-throw switch section that closes to complete a holding circuit through the jumper 55' and the lead 55 which is connected to the + terminal

5 through the holding contacts of relay CR. Energization of relay RS opens the holding circuit of relays K, H and HS that was previously completed through the back contact of the outer switch section of relay RS.

The stepping of the relay R is interrupted when the blade of the bank R₁ is short of its end contact by the number of steps that the blade of switch E is beyond its zero contact. The position of the blade of bank R₁ is therefore a measure of the number of word spaces that should receive (n-1) escapement units, and the control system for increasing the word space additions to n units (when such increase is required for perfect justification) includes the following elements and circuit connections. The blade of switch bank R₂ is connected to the + terminal, its last contact is left open, and the remaining contacts are connected to each other and, through lead 78 to the outer blade of relay WS. The associated front contact of the relay WS is connected to relay R by a jumper 79. Each energization of relay WS thus supplies a current pulse to relay R to effect a one-step advance of the blades of banks R₁ and R₂. Relay WS is energized at each entry of a word space in the transcribing of a line into the justifying typewriter JT, and relay R is thereby energized once for each transcribed word space. The blade R₁ is advanced at each release of the stepping relay R, and the blade R₁ therefore engages its next-to-the-end contact when the relay R is energized to make the last step that will move the blade R₁ to the end contact. This condition results in the transmission of a current pulse to the stepping relay SS of the word space selector when the relay R is next energized to effect the final step of the blade R₁; the current pulse being transmitted from the + terminal through the blade R₁, lead 71, the front 40 contact of the inner switch section of relay WS, and leads 64', 64. The blade of the switch bank SS2 is thereby advanced to the next higher contact to increase the width of any subsequently transcribed word space by one escapement unit.

45 The word space selector SS is reset at the completion of the transcribing of a recorded line through a circuit that includes the blade and switch bank SS1, lead 61 and the contacts of stepping relay SS, the inner switch contacts of relay CR, and leads 63, 64. The holding circuit of relay CR is broken by the energization of the end-of-line relay EL and the contacts of relay CR then close to complete the homing circuit for the stepping relay SS.

55 Non-justification

60 Justification of the line length may not be desirable, for example in the typing of the short final line of a paragraph, and the apparatus therefore includes control circuits that prevent the described operations of the justification computing and control elements. The switch 80 is closed by depressing the "non-justifying" key, and connects the + terminal to the non-justifying relay 65 81 and, through lead 82, to the relays H and HS. Energization of these relays serves, as described above, to reset the word space counter S and the line length counter U. The normally open outer set of contacts of the relay 81 complete an energizing circuit for the relay R', and thereby supply a current pulse to the trip magnet 11e to reset the escapement mechanism V1. This circuit includes leads 55'' and 75' that extend from the contacts of the relay 81 to the lead 55 (that is 70 75 connected to the + terminal through the contacts

of relay CR) and the energizing lead 75 of relay R', respectively. The blade of the normally open inner set of contacts of relay 81 is connected by lead 83 to the relay CS, and relays CS and CR are thereby energized when the non-justifying key is depressed.

The same resetting operations take place when the "error" key switch 42 is closed as the error relay 41 is connected in series with relays H and HS by jumper 84 and lead 82. The energization of the error relay does not, however, energize the carriage return relay CR.

Carriage escapement control

A portion of the circuits for controlling the advance of the carriage escapement V2 by switch bank SS2 is shown diagrammatically in Fig. 3. The first few contact points of the switch bank are consecutively numbered on the drawing, the "home" contact is identified by the character *h*, and the carriage advance resulting from the energization of the several stop solenoids 10' of the carriage escapement is indicated, in escapement units, by the numerals below the respective stop solenoids.

The illustrated escapement control is based upon a measurement, in the line length counter U, of 4 escapement units for each word space that is recorded in the line. The contact point "1" of the switch bank SS2 is connected by a line of the cable 67 to the stop solenoid 10' that will limit the carriage advance to 4 escapement units, and the subsequent contact points are connected in sequence to other stop solenoids 10'. The particular carriage escapement that will be described hereinafter provides a maximum word space width of 15 escapement units, and the "12" contact of the switch bank SS2 is therefore connected to the stop solenoid 10', not shown in Fig. 3, that sets the escapement V2 for an advance of 15 units.

The justification computing system will impart at least one advance to the blade of the switch SS2 even in the case of a composed line of exactly the desired length, and the described circuit connections add $(n-1)$ units to the recorded word space width of four escapement units when the blade engages the contact *n* corresponding to the number of steps in the primary computation of justification. The illustrated position of the blade on contact "1" indicates that at least some of the word spaces of the typed line will not be increased above their recorded value of 4 escapement units. In the special case of a composed line of exactly the desired line length, no justification is required and the blade of switch bank SS2 will remain on the "1" contact throughout the transcribing of the recorded line. In the case of a line shortage of *u* escapement units, the relay R makes one step for each transcribed word space and the blade of bank R1 reaches its home point to transmit a current pulse to relay SS during the transcribing of the recorded line. The resulting advance of the blade of bank SS2 to the next higher contact will condition the next higher stop solenoid 10' for actuation upon the transcribing of the remaining word spaces.

The blade of switch bank SS2 remains at its home contact *h* when the non-justifying key switch 80 is closed to initiate the transcribing of the recorded line. Contact *h* is connected to contact "3," and the width of each word space is

therefore equal to 6 escapement units when the recorded line is transcribed without justification.

Transcribing from memory unit

As described above, the energization of the carriage return relay CR supplies current to the pulsating relays I, IS to effect the justification computing operations. The relays I, IS also supply current pulses to the record-advancing solenoid of the memory unit in which the line or series of key actuations was recorded. The relay CR is shown as de-energized in Fig. 2a, and this condition corresponds to the completion of a transcription from memory unit M' into the justifying typewriter JT. When relay CR was first energized at the completion of a recording in memory unit M'', the solenoid 56 was energized to open the circuit to solenoid 58, thereby to adjust the switches of transfer device Tr for a recording in the memory unit M' and a transcription from memory unit M''.

The impulse relays I, IS were energized, as stated above, when the carriage return relay CR was energized, and the "hot" lead 54 was intermittently connected by impulse relay I to lead 37 that extends, through contacts of relay 29', lead 35' and switch section 28 of the transfer device, and lead 27'' to the record-advancing device 26'' of memory unit M''. The recording bands were thereby stepped around to bring the first recorded signal immediately adjacent the decoding switches 20. The clutch switch 32'' was then opened by the measuring device to open the energizing circuit of relay 29'', whereby the switch blades of that relay assumed their illustrated positions. The further transport of the recording bands by current pulses to the solenoid 26'' resulted in closures of the decoding switches 20 and the transmission of code signals to the decoding relays D to energize the type bar actuating solenoids of the justifying typewriter JT. The recorded line was transcribed, with the word space widths adjusted as previously described for justification of the line, and the final line signal energized the end-of-line relay EL and transmitted a current pulse to the magnet O of the justifying typewriter to return the carriage. The energization of the relay EL opens the holding circuits of the relays CR and R'. The de-energization of relay CR closes the homing circuit of the stepping relay SS, and the blades are advanced until the blade of switch bank SS1 reaches its last or home contact.

All parts of the apparatus are then in the positions illustrated and in condition for initiation of a recording of a series of key operations in the memory unit M'.

Decoding relays

The circuits of the decoding relays D, the decoding switches 20 of memory unit M'', and typical character and operations-controlling solenoids are illustrated in Fig. 4. The decoding switches 20 of memory unit M'' are connected to the front contacts of the switch section 23 of the transfer device Tr, as illustrated in Fig. 2c, and the decoding switches of memory unit M' (not shown in Fig. 4) are connected to the back contacts. The closure of one or more of the six decoding switches 20 results in the selective energization of the decoding relays D1—D6 that each have double throw switches, i. e. a blade or blades moving between front and back contacts in accordance with the energized or de-energized condition of the relay. The first stage of the decoding relay system

comprises the relay D1 that is energized by a closure of the "1" decoding switch 20 to move the single movable blade of the relay to energize its front contact, the blade being connected to the + terminal through lead 86 to the inner normally open switch section of the impulse relay I. The second stage includes two movable switch blades that are connected to the front and back contacts, respectively, of relay D1 of the first decoding stage, and the third stage includes four movable switch blades connected to the several front and back contacts of the second selection stage. This geometric expansion of the code selection network will require 32 movable blades in the sixth stage if the maximum number (64) of code selections is desired. A lesser number of code selections is sufficient for the usual typewriter keyboard, and some of the circuits of Fig. 4 are therefore bypassed around certain selection stages or relay switches. For example, at the central portion of Fig. 4, the lead corresponding to the code selection "456" does not extend through the switches of relays D2 and D3 in the fifth and sixth selection stages. This means that the code combinations "2456," "3456" and "23456" are not employed to identify key operations.

A single relay may be employed for each selection stage but considerable power would be required to operate the final stage relay which, as indicated above, would have about 30 movable blades. It is convenient to employ a number of commercial telephone art relays of the four-pole double-throw type, and to "reflex" the geometrically expanding code selection network to obtain some equalization of the number of relays D2 to D6 that are controlled by the switches 20 that correspond to the code identifications "2" to "6" respectively. This reflexing is effected, as illustrated in Fig. 4, by connecting the back contact of relay D1 to a blade of a relay D6, and connecting the front contact of relay D1 to a blade of a relay D2. Since the relays D2 and D6 are of the four-pole type, the remaining movable blades of these relays are available for inclusion in subsequent code selection stages. For clarity of illustration, the six code selection stages are shown as laterally spaced rows of groups of vertically aligned relay switch systems, and those relays that have switch contacts in different stages are illustrated in solid line in one stage and in dotted line in the other stages. For example, the three double-throw switches at the bottom of the final selection stage and the upper switch system of the second selection stage are controlled by a single relay D6. Similarly, the relay D2 that is shown in solid line in the second selection stage has three movable switch blades in the fifth stage, as is indicated by the dotted line showing of a relay D2 in that stage.

The distribution of decoding relays D2 to D6 in the different code selection stages may be varied and the arrangement shown in Fig. 4 is to be understood as illustrative of one practical system for reducing the number of "standard" relays of identical design that are required in a code selection system of several stages. As illustrated, the third selection stage includes relays D3 and D5 that have other contacts in the sixth and the fifth selection stages, respectively. The fourth selection stage includes two relays D4 and the fifth selection stage includes a relay D2, a relay D5, and some of the contacts of other relays D2 and D5. The sixth selection stage comprises three relays D3, three relays D6, and some contacts of additional D3 and D6 relays.

The several code combinations that may be established by the closure of one or more of the six decoding switches are indicated in Fig. 4, and the circuits corresponding to some code selections are illustrated. The majority of the code selection circuits extend to solenoids that actuate type bars of the justifying typewriter, for example the code line "25" is connected to the solenoid Oa that actuates the a type bar. The other terminal of solenoid Oa extends through lead 87 to the switch system of the "upper case" relay UC and then through the selected line of the escapement control cable 8' to stop solenoids 10' of the second variable escapement V2, see Figs. 2c and 3. The "shift" solenoid OU and the relay UC are in series and energized through the decoding line "2," and the contacts of relay UC complete a holding circuit for solenoid OU and relay UC that includes the normally closed contacts of the "lower case" relay LC. The relay LC is energized through the code line "5" to open the holding circuit of the upper case relay and solenoid, thereby permitting return of the carriage to its normal lower case position.

The word space relay WS is energized through the decoding line "1" and lead 65. As described above, the circuit of relay WS is completed through the blade SS2 of the space selector switch, a line of the escapement control cable 67, and the carriage escapement mechanism V2 of the justifying typewriter JT. The end-of-line relay RL is energized through the decoding line "4" and lead 60, and its circuit to ground is completed through the lead 60' and the solenoid O that trips the carriage return mechanism of the typewriter.

Line length and word space index

An index is provided on or above the keyboard to register the length of the composed line and the number of word spaces. This index, Fig. 5, is preferably an elongated opaque panel 90 with two rows of apertures 91 behind which small neon lights 92, see Figs. 6 and 7, are arranged. The legends "Line length" and "Word spaces," and the arrows adjacent the rows of openings indicate that increments in the line length and in the number of word spaces are measured from opposite ends of the panel. The amount of justification that can be added to a composed line depends upon the number of word spaces in the line and, for any given line shortage, there must be a certain number of word spaces for justification. The reversed sense of measurement of the line length and the number of word spaces provides the operator with a definite indication as to the possibility of justifying the composed line as the lighted neon tube of the word space index will be at the left of the lighted tube of the line length counter when there are sufficient word spaces for the justification of the composed line.

As shown in Fig. 6, the neon tubes 92 of the line length index are controlled by a switch bank U3 of the stepping switch U of the line length counter. The blade of this switch bank is connected to one terminal of a 110 volt alternating current source through a resistor 93 of about 100,000 ohms. The first portion of the line length is not registered in the index since the composed line length must be approximately the desired line length before justification is possible. The first neon lamp may be connected to the "17" contact of bank U3, which contact represents an accumulated line length of 42 out of the possible 50 rotations of the escapement shaft 9, each rota-

tion being the equivalent of 20 escapement units. A number of the adjacent contacts, each representing an additional rotation of the shaft 9, are connected to individual neon lamps 92 but the final switch contacts of bank U3 are each connected to four neon lamps in parallel, the correspondingly arranged lamps of each group being returned to the other terminal 94 of the alternating current source through the four segments of a rotary switch 95 which has a contact arm fixed to the shaft 9 of the variable escapement VI. The final portion of the composed line is thereby registered in terms of quarter-rotations of the shaft 9, i. e. the lamps are lighted in succession upon line length increments of four escapement units. Inspection of the wiring will show that "sneak" circuits are established through the contacts of the switch 95, each sneak circuit including three neon tubes in series with each other and shunted across the neon lamp that is directly connected between the "hot" contact of the switch bank U3 and the segment of switch 95 that is engaged by the rotary switch arm. The lamps of these sneak circuits will not be lighted as the voltage drop across each of the three lamps in series is not sufficient to establish conduction.

The lamps 92 of the word space index are controlled by the bank S3 of the word space counter S. The blade of switch bank S3 is connected to a terminal of a 110 volt alternating current source through a resistor 95, and contacts of the bank S3 are connected to the lamps 92 that have a common return lead to the other terminal of the current source. The number of registered word spaces may be in excess of the number of neon lamps 92 in the word space index when, as shown, only the first group of switch contacts are individually connected to neon lamps, and alternate contacts of the switch bank S3 are left open in the upper range of word spaces.

Special keys

As is customary in electrically actuated typewriters, the keyboard KS will have the usual tabulating keys and paper advance key but the switches and circuits of these keys are not illustrated as their coding relays are similar to the coding relays of the several characters except that they do not include an escapement control switch section e. Paragraph indentations are provided by a tabulation key that registers a blank space of a definite number of escapement units, for example 18 escapement units, in the variable escapement mechanism VI and places a code signal on the associated memory unit for the entry of a blank at the beginning of the transcribed line.

First variable escapement

Appropriate physical structure for the variable escapement VI is illustrated in Figs. 8 to 12b inclusive. The shaft 9 is journalled in a base plate 98 and sub-base 99 that is supported from the base plate by pillars 100. The trip solenoids 11, 11e and the stop solenoids 10 are supported on the base plate 98, and the armatures of solenoids 10 carry or otherwise actuate stop rods 101 that extend through an arcuate wall 102 and are normally retained in retracted, inoperative position by springs 103. The stop rods 101 cooperate with a stop arm 104 that is slidably and rotatably supported on the shaft 9 by a hub 105, the arm being urged in a counterclockwise direction by a relatively light torsion spring 106 that is anchored on the lift bar 107 that extends between the 75

armatures of solenoids 11, 11e. The arm 104 has a depending lug or tooth 108 that seats between teeth of the escapement wheel 109 of shaft 9 when the arm 104 is in normal position, Figs. 12 and 12a. The hub 105 is displaced axially to move the lug 108 away from wheel 109 by the trip lever 110 that is coupled to the lift bar 107 by a stiff spring 111, the lever being pivoted on a strap 112 that has an upturned flange 113 that is notched to receive and guide the lever 110. The lever 110 is yieldingly retained in normal position by a spring 114, Fig. 10, and is lifted into the position shown in Fig. 12b when the trip solenoid 11 is energized or, alternatively, into a somewhat higher position when the trip solenoid 11 and the resetting solenoid 11e are simultaneously energized.

The lever 110 has a finger 110a that normally lies below the escapement wheel 109 and moves into an intertooth space of the escapement wheel 109 when the lever 110 is lifted by the solenoid 11, Fig. 12b. The finger 110a thus locks the wheel 109 against rotation when the stop arm 104 and its lug 108 are lifted for a controlled advance of the escapement wheel 109. The trip lever 110 has a second and longer finger 110b that is raised into position to engage a resetting stop 115 on the wheel 109 when the lever 110 is lifted simultaneously by solenoids 11 and 11e for a resetting of the escapement mechanism at the end of a computation of the justification. The fingers 110a and 110b are so spaced that the finger 110a clears the wheel 109 after the finger 110b is in position to engage the resetting stop 115.

The shaft 9 is urged clockwise, as viewed in Figs. 8 and 10, by a torsion spring unit 116 that is continuously maintained in wound condition by shaft 117 of a motor, not shown in Fig. 9, that is controlled by switch 118 which is actuated by 40 a nut 119 that travels along the threaded end of shaft 9. The nut 119 and spring unit 116 have cooperating members 120 for rotating the nut 119 on the shaft 9 to displace the nut axially to open the switch 118 when the torsion spring unit is 45 fully wound. Step rotations of shaft 9 displace the nut axially in the opposite direction to close the motor switch 118 before the torsion spring is fully unwound. The general design and structural details of motor-operated spring drives of this type are well known in various arts.

The end of the stop arm 104 normally engages the right edge of the flange 113 of strap 112 to prevent clockwise rotation of shaft 9 by the spring drive mechanism, since the lug 108 of arm 104 is engaged with the escapement wheel 109. Upon energization of a stop solenoid 10, for example the trip solenoid for 6 spaces which is shown in actuated position in Fig. 8, the associated stop rod 101 is moved inwardly and the trip solenoid 11 is simultaneously energized to lift the trip lever 110 into the position shown in full line in Fig. 12b. The lifting of lever 110 frees the lug 108 from the escapement wheel 109, and the stop arm 104 is rotated counterclockwise by spring 106 to engage the projected stop rod 101. The escapement wheel 109 is locked against rotation at this time by the finger 110a of the lever 110. Upon de-energization of solenoids 10 and 11, the lever 110 is returned to normal position to engage the lug 108 of stop arm 104 with the escapement wheel. The torsion spring unit 116 then rotates the shaft 9 and wheel 109 clockwise until the stop arm 104 engages the flange 113 of the strap 112.

A shock-absorbing system for cushioning the

impact of arm 104 on flange 113 is provided by pivoting the strap 112 on a stud 121 for angular movement in frictional engagement with a leaf spring 122, the strap 112 being normally retained in radial alignment with the shaft 9 by a spring 123 that urges the strap 112 towards an abutment or stop 124. The flange end 113 of the strap 112 is driven towards the left, Fig. 10, when it is hit by the end of the stop arm 104, and the energy stored in the rotating stop arm and associated elements is dissipated in moving the strap 112 angularly with respect to the friction spring 122 and in compressing the spring 123. The spring 123 is relatively stiff and restores the strap 112 to normal position when it is displaced, as shown in Fig. 15, by the stop arm 104.

The illustrated escapement wheel 109 has 20 teeth but the maximum escapement step is only 18 teeth since the stop flange 113 prevents a complete rotation of the stop arm. The left face of the flange 113 is accurately located to serve as a stop for an escapement advance of 18 units when the solenoid 11 is energized without simultaneously energizing one of the stop solenoids 10. The 20-point switch E, see Fig. 2b, takes the form of a plate 126 of insulating material that is suspended below the base plate 88, a circular array of switch contacts 127 that extend through the plate 126, and a radial contact arm 128 carried by an insulating cylinder 129 that is fixed to the shaft 9, see Figs. 8 and 11. The circuit connection to contact arm 128 is through the collar 130 on the cylinder 129, and the brush contact 131.

The cam 14 for operating the switch 13 of the line length counter is integral with the insulating cylinder 129. The switch 95 of the line length index, see Fig. 6, comprises the four quadrant contacts 95a on the insulating plate 126 and the contact arm 95b that is carried by the insulating cylinder 129 and fed through the slip ring 132 and brush 133.

Carriage escapement mechanism

The escapement mechanism V2 of the justifying typewriter, as illustrated in Figs. 13 and 14, is similar to the escapement mechanism of the line length counter and those elements of the carriage escapement that are substantially identical with elements of Figs. 6 to 12 are identified by primed reference numerals but will not be described in detail. The carriage escapement mechanism does not include switch systems corresponding to those of the escapement V1 that are illustrated in Fig. 11.

The escapement shaft 9' is urged clockwise, as viewed in Figs. 13 and 15, by a torsion spring unit within the hollow pulley 116' that is driven from the motor 135 by a belt 136. The motor circuit includes the switch 118' that is controlled by the nut 119' that is displaced along the threaded sleeve 137 on shaft 9' in accordance with the stressed condition of the torsion spring.

The worm 134 is fixed to shaft 9' and in mesh with the worm wheel section of a sleeve member 134a that is rotatable on and has a one-way pawl and ratchet connection to the escapement control shaft 134b, see Figs. 15 and 15a. The shaft 134b carries a gear 134c that meshes with the carriage escapement rack 134d that is urged towards the right, as viewed in Fig. 15, by the usual spring, not shown. A ratchet member 134e is fixed to the shaft 134b for cooperation with a pawl 134f that is mounted on the sleeve member 134a.

Each transcribing of a character or a word 75

space from a memory unit energizes the carriage escapement control V2 to effect a predetermined measured rotation of the shaft 9', worm 134 and worm wheel member 134a. This permits a measured advance of the typewriter carriage. Upon energization of the end-of-line relay EL, the carriage return solenoid O and the resetting trip solenoid 11'e are energized. The sleeve member 134a and its worm wheel do not rotate upon this return movement of the carriage escapement rack 134d in view of the pawl and ratchet connection, but the sleeve member is reset to a definite zero position as it meshes with the worm 134 on the shaft 9' that has a definite zero position determined by a resetting stop similar to the above-described resetting stop 115 of the variable escapement V1. The left-hand margin of the printed matter may be adjusted in the usual manner by a movable stop member, not shown. This adjustment is relatively coarse and each adjustment step is equal to the number of escapement units (two units in the illustrated embodiments) corresponding to a one-tooth movement of ratchet wheel 134e with respect to the pawl 134f.

Memory unit

The memory unit or units which record the typewriter key operations and subsequently transcribe the recorded operations to the justifying typewriter may be of various types and of different designs in any selected type. A coding of the key operations is desirable to reduce the dimensions of the record medium but is not essential. The record medium may be of the closed band or rotating cylinder type, or may be an endless tape such as employed in teletype and cable transmission systems. The magnetic type of record tape is well adapted for use in the memory units but, as a typical embodiment of the invention, a mechanical type of recording system is illustrated in Figs. 16 to 25 inclusive.

The memory units M', M'' are of identical design and all parts of each memory unit are assembled on a base plate 138. A drive shaft 139 carries three toothed pulleys 140, and three idler pulleys 141 are individually mounted in spaced relation to the driving pulleys. Endless notched bands 142, with openings to take the teeth of the pulleys, extend around the cooperating sets of driving and idler pulleys, and resilient recording clips 143 are mounted upon the bands. The clips fit within the lateral notches of the bands and have inturned ends 143a that retain the clips on the bands, the sides of the clips having inwardly extending ridges 143b, see Figs. 24 and 25, that permit a seating of either edge of a clip 143 in alternative positions with respect to its supporting band 142. Six recording magnets 19 are arranged across the ends of the recording bands for adjusting the clips, as will be described in detail hereinafter.

The reduced diameter end of the shaft 139 extends into the bore of, and rotatably supports, a sleeve that has a threaded portion 144, a spool portion 145 and a clutch pin 146 for seating within an aperture 147 of the band-advancing ratchet wheel 148 that is secured to the drive shaft 139. A nut 149 is loosely threaded on the threaded sleeve portion 144 and may be normally held against rotation, by gravity, by its radially extending lug 150 that serves as an actuator for the clutch switch 32. The sleeve member is moved axially into clutch-engaging position by the rod extension 33a of the armature of the clutch solenoid 33, Fig. 16, and is released by the

spiral spring 139' when the solenoid 33 is de-energized. The nut 149 must turn with the threaded sleeve portion 144 when rotation of the latter within the nut has carried the pin 149a into engagement with a radially extending stop surface 145a on the spool portion 145 or with a stop pin 149b on the split collar 151 that is adjustable along and clamped to the threaded sleeve, Fig. 19a. A cord 152 is wound upon the spool section 145 during the advance of the bands 142 when the clutch pin 146 locks the sleeve to the ratchet wheel 148, the cord being tensioned by a spring 153 to rotate the sleeve counterclockwise when the clutch pin 146 is freed from wheel 148 by the de-energization of the clutch solenoid 33.

The clutch elements are illustrated in Figs. 16 to 19 in the positions that they assume at the close of a resetting operation. The spring 153 and cord 152 rotated the sleeve until the threaded portion 144 turned within the nut 149 to bring the stop 145a of the spool against the pin 149a of the nut, and the nut then turned with the sleeve until the lug 150 engaged the lower face of the blade of switch 32 to stop the rotation. Upon the next recording in the memory unit, the clutch solenoid 33 will be energized and the sleeve will be locked to the ratchet wheel 148 by the clutch pin 146. The threaded sleeve portion 144 will then rotate clockwise, Figs. 19 and 19a, and the lug 150 of nut 149 will be below the nut upon the completion of the first quarter-turn of the threaded portion 144. The weight of the lug 150 may prevent rotation of the nut 149 for a limited period if the nut is loosely threaded on the portion 144, or the nut may turn with the threaded portion 144 until lug 150 engages the upper face of the blade of switch 32. In either event, the nut 149 will not develop sufficient pressure of lug 150 upon switch 32 to open the same until the continued rotation of portion 144 brings pin 149a into engagement with the pin 149b of the stop collar 151. The nut will then rotate with the ratchet wheel 148 to force the lug 150 clockwise with sufficient force to deflect the movable blade of switch 32 and open the latter. The opening of switch 32 de-energizes the clutch solenoid 33, thus releasing the clutch pin 146 from the ratchet wheel 148, and the tensioned cord 152 then rotates the armature sleeve to restore the several parts to their illustrated positions.

The sliding pawl 154 of the band-advancing mechanism is moved downwardly by the solenoid 26, see Figs. 18 and 19, to engage the next tooth of the ratchet wheel 148 and to compress the spring 155 that imparts the active stroke to the pawl upon the de-energization of the solenoid. A latch spring 156 engages the wheel 148 to prevent reverse rotation, and a stop 157 is positioned adjacent the free end of the pawl 154 to hold the same against the ratchet wheel, thereby to prevent an over-running of the ratchet wheel and recording band system.

The mechanism for selectively displacing the opposite edges of the recording clips 143 with respect to the endless bands 142 is shown in detail in Figs. 20 to 22 inclusive. Two coding magnets 19 are associated with each band, and their armatures 158 have extensions 159 coupled by links 160 to the oppositely arranged recording levers 161. The levers are mounted upon the arms of a Y-shaped plate 162 that is supported above the base plate 138 by a pillar 163. The rounded ends of the levers 161 are normally held out of engagement with the clips 143 by a spring 164 which

spreads the ends of the levers 161 apart and thus draws the armature extensions 158 into engagement with a stop bar 165 that is mounted on the plate 162. Upon energization of a recording solenoid, the associated lever 161 is rocked to press the rounded lever end against the adjacent side portion of the clip 143 with a rubbing motion that forces the clip towards and laterally of the supporting band 142. The ridge 143b is forced beneath the band 142, and the resilient clip then contracts to seat the inner groove of the clip against the band 142, see Figs. 21, 24 and 25.

The flanged ends 143a of the code-recording clips are thus displaced inwardly in accordance with the code-selected energization of the six solenoids 19, and the displaced ends 143a actuate the decoding switches 20 during the transcribing from the memory unit. The decoding switches 20 are mounted upon opposite sides of the pillars 163, and spaced from the recording levers 161 by two "steps" of the band travel. Resetting horns 166 project forwardly from the arms of the plates 162 to engage the rounded advance edges of the displaced flanges 143a as the bands are advanced one step beyond the stage at which the flanges actuate the decoding switches. The horns 166 are appropriately shaped to force the edge of the clip laterally and outwardly to carry the ridge 143b beyond the outer face of the band 142.

Error control in memory unit

The adjustable collar 151 is so positioned on the threaded sleeve portion 144 that the lug 150 of nut 149 opens the clutch switch 32 when the recording bands have advanced two steps less than one complete cycle, i. e., when the set of clips 143 that recorded the first code combination after the energization of the clutch solenoid 33 are under the decoding switches. The supply circuit to the decoding switches is open so long as the clutch solenoid 33 is energized, and the clutch switch 32 opens to de-energize the solenoid 33 only when the recording bands have advanced, after the energization of the solenoid 33, to bring the first recorded signals into position under the decoding switches. The clutch solenoid 33 may be energized to terminate a recording cycle by closing the "Error" key switch 42; thereby energizing relay 41 which short-circuits the clutch solenoid 33 through the grounded lead 40, switch section 38 of transfer device Tr and jumper 38' or 38" to the associated solenoid supply lead 31' or 31" respectively.

The clutch pin 146 is momentarily released when the "Error" key switch is closed, and the travelling nut 149 is thereby reset to its initial position. The clutch solenoid 33 is again energized upon the release of the "Error" key switch, and the parts are in condition to start the re-recording of the erased line. All clips 143 that were displaced prior to the actuation of the "Error" key switch will actuate the decoding switches 20 but no signals will be transmitted to the decoding relays until the clutch switch 32 is opened by the lug 150 of the nut 149.

Operation

The method of operation of the self-justifying typewriter will be apparent from the foregoing descriptions of operations of the principal components of the apparatus. The typist operates the keys of the keyboard KS in the usual manner, and the sequence of the key operations is recorded

in one of the memory units M', M''. The computation of the line justification is initiated by the closing of the carriage return switch 52, and transfer device T₇ is simultaneously operated to condition that memory unit for a transcribing operation. The recording bands of the memory unit are advanced by current pulses from the impulse relays I, IS during the computation of the justification and, after the blade of the word space switch bank SS2 and the blade of the negative remainder counter RI have reached their computed positions, the further advance of the recording bands of the memory unit opens the clutch switch 32, thereby deenergizing the associated clutch relay 28' or 28'' to connect the + terminal to the decoding switches 20. The subsequent step-by-step advances of the bands operate the decoding switches to transmit current pulses to the decoding relays D1 to D6, and the circuits thus established through the decoding network selectively energize the operating solenoids of the justifying typewriter JT in accordance with the sequence of key actuations that was previously recorded on the bands of the memory unit. The final coded signal of the composed line energizes the end-of-line relay EL and the solenoid O that trips the carriage return mechanism of the justifying typewriter. Energization of relay EL opens the holding circuit of the relay CR, and back contacts of the latter complete a homing circuit for the resetting of the word space selector SS.

It is to be understood that the invention is not limited to the particular embodiment that is herein illustrated and described, and that various changes may be made in the component parts, and in their designs and relationships without departure from the spirit of my invention as set forth in the following claims.

I claim:

1. A variable escapement comprising a shaft having a toothed wheel fixed thereto, an advance-controlling member mounted on said shaft for axial and rotary movement, said member including a locking portion normally engaged with said toothed wheel and a stop portion, a stop member with which said stop portion is normally engaged, means to free said locking portion from said toothed wheel and to re-engage the same with the toothed wheel after a displacement of the stop portion from said stop member through a selectively controlled angle, and means for advancing said shaft to re-engage said stop portion with said stop member after an angular displacement of said locking portion.

2. A variable escapement as recited in claim 1, wherein said locking and stop portions comprise a lug extending from said advance-controlling member.

3. A variable escapement as recited in claim 1, in combination with resilient means for maintaining said stop member in predetermined position, said resilient means yielding to absorb the shock of the impact of said stop portion upon said stop member upon an advance of said shaft.

4. A variable escapement comprising a shaft having a toothed wheel fixed thereto, spring means tending to advance said shaft, a stop member adjacent said wheel, a cooperating stop device including an arm slidably and rotatably mounted on said shaft and carrying a lug to engage said stop member and to enter the space between adjacent teeth of said wheel, a trip member operable from a normal position to free said lug from said toothed wheel and simul-

taneously to lock said wheel against rotation, spring means to rotate said arm and lug in a direction contrary to an advance of said shaft, and selectively operable stop means to limit the rotation of said arm, whereby the return of said trip member to normal position results in an engagement of said first lug with said wheel and an advance of the shaft by said spring means to seat said lug against said stop member.

5. A variable escapement as recited in claim 4, wherein said trip member includes a finger to interlock with said toothed wheel prior to the movement of said lug out of engagement with said toothed wheel.

15 6. A variable escapement as recited in claim 4, wherein said trip member is a lever having an end coupled to said arm to slide the same with respect to said shaft.

7. A variable escapement as recited in claim 4, 20 wherein said trip member is a lever having an end coupled to said arm to slide the same with respect to said shaft and a finger located below said toothed wheel, the finger being movable to interlock with said wheel before the lug is lifted to clear the same.

25 8. A variable escapement as recited in claim 4, in combination with resilient means maintaining said stop member in predetermined position, said resilient means yielding to absorb the shock of said lug on said stop member upon an advance of said shaft.

30 9. A variable escapement as recited in claim 4, in combination with means for resetting said toothed wheel and shaft in predetermined angular relation with reference to said stop member.

35 10. A variable escapement as recited in claim 4, wherein said trip member and said toothed wheel carry cooperating stop members for resetting said toothed wheel and shaft in predetermined angular relation with reference to said stop member.

40

11. A variable escapement comprising a shaft having a toothed wheel fixed thereto, spring means tending to advance said shaft, an advance-controlling member pivotally and slidably supported on said shaft, said member having a locking portion normally engaged with said toothed wheel and a stop portion, a stop member against which said stop portion is normally engaged by said spring means, means including a trip member operable from a normally inactive position to slide said advance-controlling member with respect to said shaft to free the locking portion from said toothed wheel and simultaneously to lock said toothed wheel against rotation, spring means for rotating said advance-controlling member in a direction contrary to the advance of said shaft, and selectively operable stop means for limiting the rotation of said advance-controlling member, said stop means including a plurality of solenoids and stop members movable thereby into the path of rotary movement of said advance-controlling member, whereby the return of said trip member to normally inactive position results in an advance of said toothed wheel and shaft by an angular displacement determined by the selectively operable stop means.

55 12. A variable escapement as recited in claim 11, wherein said trip member includes a finger for locking engagement with said toothed wheel prior to the freeing of said stop portion from said toothed wheel by the movement of said trip member from normally inactive position.

60 13. A variable escapement as recited in claim 11, wherein said trip member and toothed wheel

65

70

75

carry cooperating stop members for resetting said toothed wheel and shaft in predetermined angular position with reference to said stop member.

14. A variable escapement as recited in claim 11, wherein said trip member includes a portion movable into engagement with said toothed wheel upon actuation of said trip member to free said locking portion of said advance-controlling member from said toothed wheel, and a resetting portion spaced from the first portion of the trip member and movable into the path of a stop on the toothed wheel upon a further movement of said trip member to free said first portion thereof from said toothed wheel.

15. In a variable escapement, a shaft carrying a toothed wheel, means including an arm pivotally and axially supported on said shaft for controlling the advance of said shaft, said arm including a locking portion normally engaging said wheel and a stop portion normally seated against a stop member, means including a lift member for moving said arm axially, and means for moving said lift member from a normally inactive position into a position to effect an advance of the shaft or alternatively into a further position to effect a resetting of the shaft in pre-selected angular relation to said stop member; said lift member comprising a lever having a portion coupled to said arm to move the same axially of said shaft, a finger portion for locking engagement with said wheel upon a movement of said lift member that frees said locking portion of the arm from said wheel, and a second finger portion movable into the path of a resetting stop on said wheel upon further movement of said lift member to free the first finger portion thereof from said wheel.

16. In a variable escapement mechanism, the invention as recited in claim 15, wherein said means for moving said lift member comprises a lift bar having an intermediate portion connected to said lift member, and means for displacing one end of said lift bar to move said lift member axially to engage the first finger portion thereof with said toothed wheel.

17. In a variable escapement mechanism, the invention as recited in claim 15, wherein said means for moving said lift member comprises a lift bar having an intermediate portion connected to said lift member, and means for displacing both ends of said lift bar to move said first finger portion thereof through and beyond engaging position with said wheel and to locate said second finger portion thereof in the path of the resetting stop on said toothed wheel.

18. In an electro-mechanical memory unit, an endless band of flat strip character, a series of clips having ends resiliently engaging opposite sides of said band and arranged in spaced relation along the same, means for advancing said band to move said clips in succession from a recording to a transcribing station, electrically actuated means at the recording station to displace a clip transversely of the flat strip, endless band from a normal to an actuated position with respect to said band, switch means at the transcribing station including a switch actuating member located in the path of actuated clips, means between said transcribing station and said recording station to return actuated clips to normal position, and means for energizing said band advancing means to effect a one step advance of said band at each operation of said electrically actuated means.

19. In an electro-mechanical memory unit, the invention as recited in claim 18 wherein each clip extends transversely of said band and has end portions each selectively movable from normal to actuated position, and said switch means includes a pair of switches having actuating members located respectively in the paths of the opposite end portions of said clips.

20. In an electro-mechanical memory unit, the invention as recited in claim 18, wherein the edges of said band are provided with laterally aligned notches, and said clips are fitted within sets of laterally aligned notches.

21. In an electro-mechanical memory unit, the invention as recited in claim 18, wherein the edges of said band are provided with laterally aligned notches, said clips each having inturned ends fitted within sets of laterally aligned notches to retain the clip on the band, and having an inwardly extending ridge adjacent each end to permit a seating of each side of the clip in alternative positions with the ridge above or below, respectively, the band.

22. In a memory unit, an endless flexible band, a series of resilient recording clips spanning said band and having side portions resiliently pressed toward each other to grip said band, each side portion having an inwardly extending ridge permitting a seating of the associated side portion of the clip in alternative positions with respect to the band, the ridge being normally at one side of the band and movable upon a resilient deformation of the clip to the opposite side thereof.

23. In a memory unit, the invention as recited in claim 22, wherein said band is provided with laterally aligned notches, and the several clips are seated in laterally aligned sets of notches.

24. In a memory unit, the invention as recited in claim 22, wherein said band is provided with laterally aligned notches, and the several clips are seated in laterally aligned sets of notches and have inturned ends to retain the same upon said band.

25. In a memory unit, the invention as recited in claim 22, wherein said band is provided with laterally aligned notches, and the several clips are seated in laterally aligned sets of notches and have inturned ends to retain the same upon said band, the advance edges of said inturned ends being rounded for engagement with resetting means to force the side portion of an actuated clip laterally outward from and transversely of the band, thereby to shift the associated ridge of the clip to normal position at the opposite side of the band.

26. A memory unit comprising endless band means carrying recording members, means for imparting a step-by-step advance to said band means to carry said recording members in sequence from a recording station to a transcribing station, a recording circuit including means at said recording station to displace a recording member from normal to activated position, a transcribing circuit including switch operating means at said transcribing station and positioned in the path of activated recording members, restoring means between said transcribing station and said recording station for returning activated recording members to normal position, and switch means operative between alternative positions to energize said recording circuit or alternatively said transcribing circuit.

27. A memory unit as recited in claim 26, in combination with measuring means for actuating said switch means to energize said transcribing circuit, and means for coupling said measuring means to said band means, said measuring means actuating said switch means upon a predeter-

mined travel of said band means corresponding to the arrival at the transcribing station of the recording member first activated after the coupling of said measuring means to said band means.

28. A memory unit as recited in claim 26, in combination with measuring means for actuating said switch means to energize said transcribing circuit, means for coupling said measuring means to said band means, said measuring means actuating said switch means upon a predetermined travel of said band means corresponding to the arrival at the transcribing station of the recording member first activated after the coupling of said measuring means to said band means, and manually operable means to decouple said measuring means momentarily from said band means, whereby said transcribing circuit is not energized during the actuation of the switch operating means by recording members activated prior to the last coupling of said measuring means to said band means.

29. A memory unit comprising an endless band carrying recording members, a driving shaft and an idler shaft supporting said band, means for imparting a step-by-step movement to said band to carry said recording members in sequence from a recording station to a transcribing station, a recording circuit including means for displacing recording members from a normal to an activated position, a transcribing circuit including switch means operable by the activated recording members, restoring means located between said transcribing station and said recording station for returning activated recording members to normal position, and circuit energizing means for energizing said recording circuit or alternatively said transcribing circuit; said circuit energizing means including measuring means, means for coupling said measuring means to said driving shaft upon an energization of the recording circuit, and means including a switch operable by said measuring means for actuating said circuit energizing means to energize said transcribing circuit.

30. A memory unit as recited in claim 29, wherein said measuring means includes a sleeve slidably and rotatably mounted on said driving shaft; and said coupling means includes a solenoid for sliding said sleeve on said driving shaft, and cooperating clutch members on said sleeve and driving shaft engageable upon said sliding of the sleeve by the solenoid.

31. A memory unit as recited in claim 29, wherein said measuring means includes a sleeve having a threaded portion and a spool portion, a nut on said threaded portion for actuating said switch, and means including a spring and a cord wound upon said spool portion for returning said nut to a normal position spaced from said switch upon a decoupling of said measuring means from said driving shaft.

32. A memory unit of the electro-mechanical type, an endless band carrying recording members, means for advancing said band, a recording circuit network including electrically actuated means for moving the recording members from a normal to an activated position, a transcribing circuit network including switch means operable by activated recording members, and transfer means for alternatively energizing either said electrically actuated means or said transcribing circuit network.

33. In a memory unit, the invention as recited in claim 32, wherein said transfer means includes

switch means for connecting said band advancing means into the transcribing circuit network when the latter is energized and alternatively into the recording circuit network when said electrically actuated means is energized.

34. In a memory unit, the invention as recited in claim 32, wherein said transfer means includes switch means for connecting said band advancing means into the transcribing circuit network when the latter is energized and alternatively into the recording circuit network when said electrically actuated means is energized; in combination with measuring means, means for coupling said measuring means to said band simultaneously with the energization of said electrically actuated means of the recording circuit network, a switch in series with said switch means of the transcribing circuit network, and means controlled by said measuring means for closing said switch for a transcribing action.

35. In a memory unit, the invention as recited in claim 32, wherein said transfer means includes switch means for connecting said band advancing means into the transcribing circuit network when the latter is energized and alternatively into the recording circuit network when said electrically actuated means is energized; in combination with measuring means, means for coupling said measuring means to said band simultaneously with the energization of said electrically actuated means of the recording circuit network, a switch in series with said switch means of the transcribing circuit network, means controlled by said measuring means for closing said switch for a transcribing action, and manually operable means for momentarily decoupling said measuring means from said band to initiate a new measuring operation, whereby recording members activated prior to decoupling move past the switch means of the transcribing circuit network prior to the closure of said series switch.

36. A memory unit comprising band means including a plurality of flexible endless bands on which are supported six sets of transversely aligned recording elements in the form of clips having ends resiliently engaging opposite sides of said band means, means for advancing said band means to move said sets of recording elements in succession from a recording station to a transcribing station, a recording circuit network including electrically-actuated means at said recording station for selectively displacing one or more of said recording elements from normal position to activated position with respect to said band means, a transcribing circuit network including a plurality of switches at the transcribing station and positioned for actuation by the activated recording elements of the respective sets of recording elements, and means between said transcribing station and said recording station for restoring activated recording elements to normal position.

37. A memory unit as recited in claim 36, wherein said band means comprises three endless bands supported on pulleys on a driver shaft and on idler pulleys, and the recording elements associated with each band comprise the opposite ends of resilient spring clips seated on that band.

38. A memory unit as recited in claim 36, wherein said band advancing means includes a driver shaft, a ratchet wheel on said shaft, a pawl and spring means urging the same in a direction to advance the ratchet wheel and shaft, and a solenoid for moving the pawl in the opposite direction, whereby de-energization of the solenoid

results in an advance of the ratchet wheel and shaft; and said recording circuit network includes means for energizing said solenoid simultaneously with the energization of any of said electrically-actuated means.

39. A memory unit as recited in claim 36, wherein said band advancing means includes a driver shaft, a ratchet wheel on said shaft, a pawl and spring means urging the same in a direction to advance the ratchet wheel and shaft, and a solenoid for moving the pawl in the opposite direction, whereby de-energization of the solenoid results in an advance of the ratchet wheel and shaft; and said transcribing circuit network includes means for delivering a series of current pulses to said solenoid to advance said band means step-by-step to move the activated recording elements through the transcribing station.

40. A memory unit as recited in claim 36, wherein said band advancing means includes a driver shaft, a ratchet wheel on said shaft, a pawl and spring means urging the same in a direction to advance the ratchet wheel and shaft, and a solenoid for moving the pawl in the opposite direction, whereby de-energization of the solenoid results in an advance of the ratchet wheel and shaft; said recording circuit network includes means for energizing said solenoid simultaneously with the energization of any of said electrically-actuated means; and said transcribing circuit network includes means for delivering a series of current pulses to said solenoid to advance said band means step-by-step to move the activated recording elements through the transcribing station.

41. In a self-justifying typewriter, an escapement for recording the accumulated length of a line corresponding to a key-controlled selection of a series of characters of varying width, a counter for registering the number of word spaces included in the line, and signal means jointly controlled by said escapement and counter for indicating the registering of a number of word spaces sufficient for expanding the accumulated line length to a desired justified line length upon increase of the word space lengths to a fixed maximum value.

42. In a self-justifying typewriter, the invention as recited in claim 41, wherein said signal

means comprises a pair of indicating devices developing significant signals movable in juxtaposition and in opposite directions to indicate respectively the accumulated line length and the number of recorded word spaces, the crossing of the significant signals indicating the possibility of justification of the line.

43. In a variable escapement typewriter, an escapement for registering the accumulated length of a line of word spaces and variable width characters set up by actuation of the typewriter keys, said escapement comprising a rotatable shaft and stop means selectively operable by the keys for controlling the rotation of the shaft, and a line length indicator comprising a line of neon lamps and switch means controlled by said shaft to connect said lamps selectively to a current source to register complete rotations of said shaft.

44. In a variable escapement typewriter, the invention as recited in claim 43, wherein said line length indicator includes means for indicating fractional advances of said escapement shaft as its accumulated advance approaches a value corresponding to the desired justified line length; said last means comprising groups of neon lamps forming an extension of said line of neon lamps for registering complete rotations of said shaft, switch means including a contact arm and plurality of cooperating contacts, said shaft effecting relative movement of said contact arm and contacts, circuit elements connecting correspondingly arranged lamps of the several groups to the respective contacts, a lead from said contact arm to one terminal of the current source, and circuit connections from the several groups of lamps to the other terminal of said current source through said switch means, whereby successive groups of lamps are connected to said current source upon successive complete rotations of said shaft.
